UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

COMMINUTING MILL.

Application filed March 15, 1923. Serial No. 625,222.

To all whom it may concern:

Be it known that RAY C. NEWHOUSE, a citizen of the United States, residing at Wauwatosa, in the county of Milwaukee and 5 State of Wisconsin, has invented a certain new and useful Comminuting Mill, of which the following is a specification.

This invention relates in general to improvements in the construction and operation 10 of comminuting apparatus and relates more specifically to an improved screening mechanism especially applicable to rotary comminuting mills and the like.

An object of the invention is to provide 15 simple means for enhancing the capacity and the efficiency of comminuting mills and of rotary screening devices therefor.

It has been found in the operation of comminuting mills having annular rotary 20 screens for grading the material delivered from the comminuting chambers, that unless some provision is made for automatically spreading and distributing the material delivered upon the screens, the screening surfaces 25 become locally congested with material and wear out rapidly. This local congestion naturally reduces the screening and hence the discharge capacity of such mills, and the local wear necessitates frequent replacement of the screens. The present invention contemplates the provision of simple, efficient and automatically functioning 30 means for distributing the material over the entire screening surface, thereby eliminating the objectionable congestion of material and local wear on the screens.

Some of the novel features disclosed but not specifically claimed herein, form the subject of a copending application for Letters Patent, filed April 7, 1921 and bearing Serial No. 459,332.

A clear conception of an embodiment of the invention and of the operation of devices constructed in accordance therewith, 45 may be had by referring to the drawing accompanying and forming a part of this specification in which like reference characters designate the same or similar parts in the several views.

50 Figure 1 is a transverse vertical section through the division head of a combination comminuting mill provided with a screen for grading material delivered from the coarse grinding compartment of the mill.

55 Figure 2 is a fragmentary longitudinal

section through the combination comminuting mill, the section being taken along the line II—II of Fig. 1.

Figure 3 is an enlarged sectional view of the improved spreading device for distributing 60 material over the screening surface.

Figure 4 is an enlarged elevation of the improved spreading device.

The rotary comminuting mill illustrated in Figs. 1 and 2 comprises generally a rotary shell or cylindrical drum 2 the interior of which is divided by means of a partition or division head 8, into successive comminuting chambers 3, 4 having freely tumbling comminuting bodies 5, 6 therein respectively. 65 The division head 8 comprises an imperforate wall and a hold-back screen 7 spaced laterally therefrom by means of radial ribs 19 which provide segregated discharge chambers 9 between the wall and hold-back 70 screen. The hold-back screen 7 serves merely to prevent the coarse material and comminuting bodies 5 of the coarse grinding chamber 3, from entering the spaces 9, but does not prevent free passage of comminuted 75 material from the chamber 3 to the spaces 9. The spaces 9 communicate through peripheral openings 18 with the screening chamber surrounding the drum 2 and located within the annular screen 12. In order 80 to provide maximum and sufficient screening capacity, the screen 12 is laterally widened considerably beyond the side edges of the openings 18 leading from the chambers 9. For the purpose of preventing local delivery 85 of material through these openings to the screen 12, each of the openings 18 leading from the chambers 9 is provided with a spreader 11 having a discharge directed oppositely of the direction of rotation of the 90 mill. The spreaders 11 have outwardly and downwardly inclined guiding surfaces and also have laterally widened discharge edges 17 for effectively distributing the material over all portions of the laterally widened 95 annular screen 12.

The relatively fine material passing through the screen 12 is delivered by gravity into a receptacle 15 which may have liquid 100 therein as indicated. The drum 2 adjacent to the division head and on the fine grinding side thereof, is provided with one or more peripheral scoops 16 adapted to remove material from the receptacle 15 and to discharge the material through members 110

20 into the fine grinding chamber 4 wherein are located the fine grinding or finishing comminuting body 6.

The oversize material which cannot pass 5 through the screen 12 is automatically returned to the coarse grinding chamber 3 during the operation of the mill by means of return shoes 13 which during rotation of the mill deliver such oversize material 10 through conduits 10 and return orifices 14 into a medial portion of the chamber 3. The portion of the mill adjacent to the screen 12 and scoops 16 may be provided with a suitable stationary housing 21 which 15 is readily removable to permit access to enclosed elements such as the screen 12.

During normal operation of the comminuting mill, the material reduced by the tumbling comminuting bodies 5 in the coarse 20 grinding chamber 3 is delivered past the hold-back screen 7 into the chambers 9 and from thence through the discharge openings 18 upon the spreaders 11. The laterally widened discharge edges 17 of the spreaders 25 11 effectively distribute the comminuted material over the entire surface of the annular screen 12. The particles of material which are sufficiently fine to pass through the perforations of the screen 12 are delivered by 30 gravity into the receptacle 15. The larger particles which cannot pass through the perforations of the screen 12 roll along the inner surface thereof and are finally picked up by the shoes 13 and are delivered through 35 the passages 10 and return openings 14 back into the coarse grinding chamber 3 for further reduction. The fine material deposited within the receptacle 15 is eventually removed and elevated by the scoops 16 which 40 deliver the elevated material to the fine grinding chamber 4 of the mill through the injection nozzles 20. In the chamber 4 the fine material is further reduced by the tumbling comminuting bodies 6, the material being eventually discharged from the 45 mill in a well known manner.

It will be obvious that the spreaders 11 effectively distribute the material upon the annular screen 12 and prevent local congestion 50 and consequent rapid wearing of the screen. By providing the spreaders 11 the screen 12 may be laterally widened to permit free discharge of all material which has been sufficiently reduced, from the coarse 55 grinding chamber 3, thereby permitting the comminuting bodies to act most efficiently upon the remaining particles.

It should be understood that it is not desired to limit the invention to the exact 60 details of construction herein shown and described for obvious modifications may occur to persons skilled in the art.

It is claimed and desired to secure by Letters Patent:

1. In combination, a rotary drum, an annular screen rotatable with said drum and having side walls, and a spreader located within said screen and between said walls, said spreader being formed to direct material delivered from said drum over all 65 portions of said screen.

2. In combination, a rotary drum, an annular screen surrounding and rotatable with said drum, and a spreader formed to direct material delivered from said drum over said 75 screen in directions parallel to the axis of said drum.

3. In combination, a rotary drum having a peripheral discharge opening, a screen rotatable with said drum and having side 80 walls, said screen and said walls extending axially of said drum beyond said opening, and a spreader located within said screen and between said walls, said spreader being formed to direct material delivered to said 85 screen through said opening laterally over all portions of said screen.

4. In combination, a rotary drum forming a comminuting chamber and having a peripheral discharge opening communicating with said chamber, a screen rotatable with said drum and extending transversely relative to the direction of movement of said drum beyond said opening, and a spreader 90 for directing material from said opening laterally over said screen.

5. In combination, a rotary drum forming a comminuting chamber and having a peripheral discharge opening communicating with said chamber, an annular screen 100 surrounding and rotatable with said drum, said screen extending transversely relative to the direction of movement of said drum beyond said opening, and a spreader for directing material delivered from said opening 105 laterally over said screen and in a direction opposite to the direction of rotation of said drum.

6. In combination, a rotary drum forming a comminuting chamber and having a series 110 of peripheral discharge openings communicating with said chamber, an annular screen surrounding and rotatable with said drum, said screen extending longitudinally of said drum beyond said openings, and a spreader 115 associated with each of said openings for directing material delivered through said openings over all portions of said screen and in a direction opposite to the direction of rotation of said drum.

In testimony whereof, the signature of the inventor is affixed hereto.

RAY C. NEWHOUSE.
